DESIGN FOR A COMBINATION FAN AND TABLE

William L. Kisling, St. Louis, Mo.

Application November 17, 1938, Serial No. 81,162

Term of patent 7 years

To all whom it may concern:

Be it known that I, William L. Kisling, a citizen of the United States, residing at St. Louis, in the State of Missouri, have invented a new, original, and ornamental Design for a Combination Fan and Table, of which the following is a specification, reference being had to the accompanying drawing, forming part thereof.

The top of the cone-shaped fan reflector is covered by a flat, circular member similar to the one at the top of the unit.

I claim:

The ornamental design for a combination fan and table, as shown and described.

WILLIAM L. KISLING.
